LAMP

Samuel Stahl, Chicago, Ill.

Application February 18, 1935, Serial No. 6,955

7 Claims. (Cl. 176—1)

My invention relates to electric lamps, and includes among its objects and advantages a simplification in lamps which operate by maintaining one or more arcs inside a transparent bulb.

5 In the accompanying drawings: Figure 1 is a side elevation of a lamp according to the invention;

Figure 2 is a developed section as on the arcuate line 2—2 of Figure 3;

10 Figure 3 is a section on line 3—3 of Figure 1;

Figure 4 is a developed section, as in Figure 2, indicating an alternative arrangement for the starting resistances;

15 Figure 5 is a fragmentary side elevation of an alternative arrangement for starting the first arc; and

Figure 6 is a developed section, as in Figure 2, indicating another arrangement for the starting resistances.

20 In the embodiment of the invention selected for illustration, the lamp comprises the usual glass bulb 10 with a threaded socket 12. The stand 14 includes three tubes, 16, 18, and 20, extending in parallelism along the neck of the bulb and 25 then diverging to support the glass annulus 22 at three equally spaced points.

The arcing zone is below the annulus, and in it I position electrodes for maintaining five arcs at 24, 26, 28, 30, and 32. To deliver current to these 30 arcs, the button 34 connects with a long resistance 36 housed in the tube 18. The resistance 36 delivers current to the pillar 38 carrying the electrode 40 at its lower end. A series of similar 35 pillars 42 support bridges 44, 46, 48, and 50, carrying at their ends the electrodes for the arcs, and the last electrode 52 is mounted directly on the pillar 54 which communicates with the return resistance 56, which is a duplicate of resistance 36 and is housed in the tube 16, and 40 leads to the shell 12.

45 Shunting the arcs 24, 26, 28, 30, and 32, I provide resistances 58, 60, 62, 64, and 66. A globule of mercury 68 in the bottom of the bulb keeps the bulb at all times filled with mercury vapor at pressures depending on the temperature of the bulb. Thus at ordinary room 50 temperatures the pressure of the mercury vapor in the bulb will be approximately 1.2 microns, whereas if the bulb is heated to 350° C. the mercury vapor in the bulb will have a pressure only slightly less than atmospheric pressure.

55 The resistances 58, 60, 62, 64, and 66 each have a resistance many times the resistance of the arcs they shunt, when the lamp is heated through and operating normally, and each resistance has a

value somewhat lower than the preceding one. Good results may be obtained with shunt resistances at least ten times as high as the resistances of the arcs they shunt. The resistances 36 and 56 are relatively very low, and when line voltage 5 is first delivered to the lamp, a disproportionate share of the available energy is developed in resistance 58.

The resultant local heating in the vicinity of the arc 24 will heat the adjacent electrodes 10 and the mercury vapor around them, and the warming up of the lamp as a whole will increase the ionization until an arc is established at 24. The resulting reduced resistance in the lamp as 15 a whole will result in material increase in current which will materially increase the temperatures of the resistances 60, 62, 64, and 66.

The shunting of filament 58 will reduce the resistance in the lamp and will result in a material increase in current. Now filament 60 will 20 become incandescent because it has the highest resistance and heats the gap for the arc 26 and ionizes the mercury vapor at this point, establishing arc 26. Filament 62 now becomes incandescent because now it is the highest resistance in the circuit, and ionizes the vapor to establish the arc 28. Then filament 64 will 25 follow the same process and establish arc 30. The filament 66 will now become incandescent as the others have done and establish the last 30 arc 32. On shunting each arc an increase of current occurs in the circuit. The arcs may be arranged to open in any order, so far as their geometrical location is concerned. After all five 35 arcs are functioning, the relatively low resistances 36 and 56 remain to protect the lamp against excessive current flow. Thus, with arcs designed to operate with a fifteen volt drop and a line voltage of 120, the protecting resistances 36 and 56 will need to take care of the remaining 40 45 volts, and therefore each have a resistance about one and one-half times that of an individual arc.

The resistances designed to remain permanently in the circuit to protect the lamp may be 45 positioned anywhere in the circuit of which the lamp forms a part. In the case of inside resistances I have indicated one arrangement in Figure 2 which consists of housing them in the tubes 16 and 18 of the stand. This affords them 50 an effective radiating capacity many times greater than that of one of the arcs, so that they will not be heated materially above the temperature of their environment.

55 Referring now to Figure 4, I have indicated a

single resistance 70 spanning both arcs 26 and 28, and a single resistance 72 spanning both arcs 30 and 32. In certain types of construction the cost of manufacture is materially reduced by the reduction in the number of filaments and filament attachments. I have also indicated protective resistances 74 and 76 arranged to operate at temperatures of incandescence. This is advantageous when the uses to which the lamp is to be put make it desirable to have blended with the light from the arcs a percentage of light having the different spectral characteristics of an incandescent metal.

In Figure 6, I have indicated a further development of the same principle in the form of a single resistance 78 bridging all five arcs, and protective resistances 80 and 82 festooned from the end electrodes to additional pillars 84 and 86. This positions the incandescent filaments 80 and 82 where their geometrical location is best for effective radiation of the light from them.

Additional desirable constituents in the light from the lamp, as well as materially different starting characteristics may be obtained by the use of an additional filling of argon or other inert gases. Because the incandescent filaments are positioned close below the arcs they shunt, such a gas filling enables a relatively low degree of incandescence to generate local ionization in the gas filling that will assist the establishment of a glow discharge filled by a gas arc, and thus establish the arcs with less heating. The reduction in the necessary heat supply makes it possible to use higher shunt resistances and thus increase the efficiency of the lamp for permanent operating conditions. Also, if the filling is desired for starting only, a relatively low pressure not only facilitates the establishment of the arcs, but when the temperature has built up the mercury vapor pressure to a substantial volume, the minute amount of inert gas present will be moved substantially entirely up into the stem of the bulb by the thermal circulation of mercury vapor moving up around the arcs and down by condensation against the wall of the bulb, so that the arcs may operate in a combined atmosphere of mercury and inert gas when a substantial amount of inert gas is put into the bulb, or in an atmosphere substantially of mercury only where the inert gas is present in relatively minute quantities.

Where an inert gas filling is employed, the first arc may advantageously be arranged as in Figure 5 where the electrodes 88 and 90 are connected with the electrodes 40 and the bridge 44 respectively by resistances 92 and 94. The short gap between the electrodes 88 and 90 causes the immediate establishment of a glow discharge filled by an arc at this point, and the radiation from the small arc rapidly ionizes the space to be occupied by the long arc 24 enough to cause the establishment of the arc 24. The glow discharge and establishment of the arc may be facilitated by the use of a suitable emitter, such as a rare earth oxide, with which the surfaces of the resistances 92 and 94 need be only slightly contaminated to accomplish a large increase in ionization. After the arc 24 is established, the intensity of the arc between the electrodes 88 and 90 will be so reduced by reason of the resistances 92 and 94 that it will be relatively negligible.

Such a lamp has several interesting operating characteristics and advantages. Referring to Figure 2, by constructing all the resistances 58,

60, 62, 64, and 66 with the maximum values that can be used and still generate enough heat to start the lamp, the arcs 24, 26, 28, and 30, even after establishment, will burn with relatively low intensity until the arc 32 starts, and at that time 5 the entire lamp will blaze up with full strength. Such a lamp will be relatively slow to start, but after it is functioning, the high resistances employed in shunt will reduce to a negligible percentage the energy dissipated in those resistances. 10

For a lamp that is to be turned on and off repeatedly at short intervals and that needs to go into operation much more quickly, the use of lower resistance values, particularly for resistances 60, 62, 64, and 66, will enable the arcs 15 already established to burn much more vigorously. With such an arrangement the arcs can be established much more quickly, and the lamp will heat up much more promptly to a suitable operating condition. 20

It should also be noted that partial failure of any of the resistances 58 to 66, inclusive, as for instance due to defects in manufacture, will not render the lamp inoperative unless the failure is complete. Thus, if resistance 64 happened to 25 have a mechanical defect that made its actual resistance much higher than that intended, arc 30 might get started before arcs 28 and 26, but the lamp would still start, and after it was started, the mechanical defect would have no effect other than a slight increase in efficiency with respect to the arc 30. 30

The use for starting purposes of a heat source other than the arc itself makes it possible to design and proportion the arcs for operating conditions, substantially without regard to starting conditions. 35

Without further elaboration, the foregoing will so fully explain my invention that others may, by applying knowledge current at the time of application, readily adapt the same for use under various conditions of service. For instance, when particular portions of the spectrum are desired for use, the bulb should be of a material transparent to those wave lengths. 45

I claim:

1. In a metal vapor arc lamp, a bulb, a metal filling in said bulb, stationary terminals in said bulb for maintaining a plurality of arcs arranged in series, and shunt heating resistances for each arc, one of said heating resistances being of higher resistance than any of the rest. 50

2. In a metal vapor arc lamp, a bulb, a metal filling in said bulb, stationary terminals in said bulb for maintaining a plurality of arcs arranged in series, and shunt heating resistances for each arc, said shunt resistances having progressively decreasing resistance values, whereby said arcs are established in a predetermined sequence in the order of said resistance values, an arc adjacent the shunt of highest resistance being established first. 60

3. In a metal vapor arc lamp, a bulb, a metal filling in said bulb, stationary terminals in said bulb for maintaining a plurality of arcs arranged in series, and a separate shunt heating resistance individual to each arc and connected directly across the same, one of said heating resistances being of higher resistance than any of the rest. 65

4. In a metal vapor arc lamp, a bulb, a metal filling in said bulb, stationary terminals in said bulb for maintaining a plurality of arcs arranged in series, and shunt heating resistances for each arc, said shunt resistances having progressively 70

75

decreasing resistance values, whereby said arcs are established in a predetermined sequence in the order of said resistance values, an arc adjacent to the shunt of highest resistance being established first, the arc with the highest resistance being at one end and each adjacent arc throughout the series having a lower shunt resistance than the preceding one.

5. In a vapor arc lamp, a bulb, electrodes in said bulb for setting up a plurality of peripheral arcs substantially all in the same plane encircling the center of the bulb and spaced outwardly from said center toward the periphery of the bulb, and lead wires for delivering current to said electrodes.

10. 6. In a vapor arc lamp, a bulb having substantially the shape of a surface of revolution, and

electrodes arranged to set up a plurality of arcs encircling the axis of said surface of revolution and positioned intermediate between said axis and the periphery of the bulb, said arcs extending along the periphery of a circle only partially occupied by arcs.

15. 7. In a vapor arc lamp, a bulb, terminals in said bulb for establishing a plurality of separate arcs in series, and a single resistance shunted across all said arcs and positioned to heat and ionize the spaces occupied by all of them, said resistance being electrically connected to the remote end terminals only of the arcs at opposite ends of the series.
